UNITED STATES PATENT OFFICE

FRANK HAROLD CLAUSE, OF CAMBERWELL, LONDON, ENGLAND, ASSIGNOR TO
WADDINGTON TAMPERPROOF TAXIMETERS, LIMITED, OF LONDON, ENGLAND

TAXIMETER

Application filed June 27, 1930, Serial No. 464,288, and in Great Britain July 25, 1929.

This invention relates to improvements in taximeters, and more particularly to the road wheel and clock drive therefor.

In taximeter construction, the indicating and recording mechanisms are usually operated by a pawl on a lever engaging a hub wheel which is driven by ratchet and pawl mechanisms, in turn driven by trains of wheels from the cab road wheel and from a clock. The ratchet operated by the train which is moving at the slower rate overruns its pawl, and the pawls are therefore frequently in such a position with respect to the driving surfaces of the teeth of the ratchet that there is an appreciable lag before the pawl moves into engagement with the driving surface. Back lash or slack is thus present in the road drive and the clock trains of wheels, as the carriers of the pawls are carried forward by friction. This back lash and lag in the drive results, especially in traffic congested areas, in an appreciable loss to the taxicab proprietors, frequently amounting to 10% of the true fare, since during the time that the lag or back lash is being taken up, the drive from the road wheel train or the clock is not transmitted to the indicators to increase the value of their indication.

The object of this invention is to obviate or minimize the loss usually incurred in taximeters, due to lag and back lash between the various parts of the driving mechanism, while yet employing parts which can easily and cheaply be manufactured and assembled without undue regard for extreme accuracy.

The principle employed is the maintenance of contact between driven and driving members by means of springs. The method adopted can be varied. In the case of the clock drive the back lash is considerably reduced by deep meshing with fine (i. e. closely pitched) teeth on the gear wheels and entirely obviated when the driven wheels are kept in engagement with the driving wheels by springs. Fine teeth have hitherto seldom been employed, since they necessitate very accurate mounting of the wheels on their spindles and pivots in order to avoid too deep meshing of the gear wheels which might

stop the clock, or shallow meshing which would increase the carry forward by friction previously referred to. The method according to this invention of springing the driven wheels into the driving wheels makes 55 deep meshing possible without great accuracy in mounting.

In place of the ratchet and pawl mechanism the driven members are maintained in constant contact with the driving members 60 by spring-urged drive transmitting intermediates.

In the road drive train the gearing sometimes includes a worm and worm wheel and sometimes a bevel and crown wheel. The 65 torsion of the usual flexible shaft drive maintains the train without slack up to the worm or bevel wheel and maintains without slack part of the train where ordinary gearing is used. In this invention when worm gearing 70 is employed the train from the worm gearing is maintained according to this invention in contact by spring means and if bevel and crown wheel gearing is employed, contact would be maintained from these wheels on- 75 wards.

In the case of ordinary gearing in the road drive train, it is advisable to hold the wheel mounted on the hub-wheel drive spindle, in contact with its predecessor. 80

The springing of the hub wheel itself is not in a contrary direction, but in the direction of the drive when its driving source is stationary, the effect being the same as back springing. The full value of its free movement, which is variable as required, is thus obtained. 85

The invention is illustrated in the accompanying drawings in which Figure 1 is a sectional elevation of a taximeter constructed according to this invention, and Figure 2 a side elevation of the relevant parts removed from the taximeter casing. Figures 3 and 4 are respectively elevations at right angles to 90 one another of a modified arrangement of parts, and Figures 5, 6 and 7 detail views of the clutch devices, Figures 5 and 6 showing the clutch device employed in the arrangement of Figures 1 and 2, and Figure 7 the 100

clutch device employed in the arrangement of Figures 3 and 4.

Referring more particularly to Figures 1, 2, 5 and 6, 1 indicates the casing of a taximeter on which is mounted the usual flag 2 whose movements determine the setting into operation of the various parts of the taximeter. These parts may include a lever 3 which is adapted to be actuated by a hub wheel 4, and which effects the operation inter alia of fare indication drums 5, 6, 7 and 8, which are interconnected by gearing indicated generally at 9, 10, the hub wheel 4 being urged by a spring 42 in the direction in which it is driven when the meter is operative. These parts are well understood in the art, and further description thereof is believed to be unnecessary.

11 is the main spring barrel of the clock-work mechanism which can be wound up by a handle 12 and which drives a gear train comprising wheels 13, 14 and 15. The gear wheel 15 is in mesh with a gear wheel 16, loosely mounted on a spindle 17 which drives the hub wheel in a manner hereinafter described, the gear wheels 15 and 16 being formed with very fine teeth of cycloidal or involute form. The gear wheel 16 is fast with a plate 18 freely mounted on the spindle 17 and fast with a ring-shaped member 19 whose inner periphery is formed with a series of surfaces 20 whose slope is such as to form together with the periphery of a disc 21, a series of wedge-shaped gaps. In these gaps are located hollow clutch cylinders 22, which are urged towards the narrow end of the wedge-shaped gaps by light springs 23. The cylinders may, if desired, be replaced by rollers or wedges.

The disc 21 also co-operates with a second ring-shaped member 25 to form a second series of wedge-shaped gaps, in which are located lightly spring-pressed hollow clutch cylinders 26, this second member 25 being secured to a worm wheel 27 freely mounted on the spindle 17 to which spindle the disc 21 is secured, and the two series of wedge-shaped gaps being separated by a division ring 28.

The angle of the sloping surfaces 20 to the tangent of the disc 21 must lie between 8 and 50 12 degrees, and the inner race must be $\frac{3}{4}$ " to $1\frac{1}{4}$ " diameter for six rollers, and $\frac{1}{2}$ " to $1\frac{1}{4}$ " for three rollers.

In order to maintain the gear wheels 15 and 16 in deep mesh without however having very accurately to manufacture and locate the spindles on which they are mounted, and in order to obviate strain due to deep meshing, the spindle 17 on which the gear wheel 16 is mounted is carried in an arm 29 pivotally mounted at 30 and urged by a spring 31 so that the gear wheel 16 is maintained constantly in deep mesh with the wheel 15.

The worm wheel 27 is in mesh with a worm 65 32 fast with a spindle 33 driven in the man-

ner referred to in connection with Figures 3 and 4 from the road wheels of the taxicab.

In order to prevent back-lash between the worm 32 and worm wheel 27, the worm spindle 33 is pressed by a spiral spring 34 in a direction to take up wear, due to the thrust resulting from the transmission of the drive from the worm to the worm wheel and the worm wheel teeth are engaged by a pawl 35 extending substantially radially with respect to the gear wheel 27, the free end of the pawl being disposed for engagement with leading tooth surfaces of the wheel, the pawl being urged in a direction substantially tangential to the periphery of the wheel by means of a spring 36. The pawl, under the urge of the spring 36, tends to rotate the wheel 27 in a direction opposite to that in which it is driven by rotation of the worm. The spiral spring may be replaced by a flat spring acting on the worm or wormshaft, and the pawl 35 may be replaced by a strip of spring steel and the pawl or spring may be multiplied. Thus, the worm is constantly pressed forward to obviate any lag in drive due to wear in end thrust bearing surfaces of the worm spindle, and the teeth on the worm wheel are maintained constantly in contact with the teeth on the worm.

The hub wheel 4 is freely mounted on the spindle 17 and is fast with a plate 4' formed with an arcuate slot 37, the effective length of which can be varied by a plate 38 secured to the plate 4' by screws 39 which can, when slackened, move along a second arcuate slot 40 to cause the edge of the plate to blank-off more or less of the slot 37. Extending into the slot 37 is a pin 41, fast with a plate 42 secured to the spindle 17.

In operation, when the flag is down (i. e. in the "hired" position), the gear wheel 16 is constantly driven by the clock train and the worm wheel 27 is driven by the worm 32 so long as the taxicab is in motion. If the taxicab is travelling at a rate such that the road wheel drive is moving at a rate greater than that of the clock train, the worm wheel 27 will be driven at a greater rate than the gear wheel 16, and drive will be transmitted from the worm wheel to the spindle 17 through the hollow cylinders 26 which become wedged between the periphery of the disc 21 and the surfaces 20 on the member 25. During this time, since the disc 21 is rotating at a rate greater than that of (i. e. is overrunning) the gear wheel 16, the cylinders interposed between the member 19 and the disc 21 will be idle. If, now, the taxicab stops or slows down to a rate such that the wheel 16 is moving at a rate greater than that of the worm wheel 27, the member secured to the gear wheel 16 will at once cause its rollers 22 to become wedged, and thus the 130

drive is transmitted to the spindle 17 from the clock train, the rollers interposed between the member 25 secured to the worm wheel 27 and the disc 21 now being idle. There is thus provided a one-way clutch device, in which lag in taking up the drive is very substantially reduced. The pin 41, being at the end of the slot, due to the springing forward of the hub wheel 4 by the spring 42, is then actuated, at first idly moving in the slot until it moves into engagement with the end wall thereof, or with the edge of the plate, whereafter the drive is transmitted to the indicating and recording mechanism in the usual way. It will, of course, be understood that the period of time during which the pin 41 moves idly in the slot corresponds with the distance and/or time period which is allowed for the initial charge indicated immediately the flag is moved to the "hired" position.

It is usual to gear the taximeter to run slow, and in most taximeters the apparatus consequently runs slow not only for the initial distance or time, but for subsequent distances or times. By the adjustment device according to this invention, which device may comprise carefully placed pins or stops, though a slot is easier to regulate, it is possible to gear the taximeter to the dead limit for distance or time, and give what allowance is considered suitable by regulating the length of the slot, so that for the first unit of distance or of time the taximeter will be slow, but when the pin has idly traversed the slot, the taximeter will be exact.

In the modification shown in Figures 3, 4 and 7, the one-way clutch devices are mounted on two parallel shafts instead of on a single shaft, as in the arrangement of Figures 1 and 2. In this arrangement, the worm wheel 27 is fast with a gear wheel 43 which, through intermediate gear wheels 44, 45 and 46, drives a gear wheel 47 secured to a spindle 48 fast with which is the outer member 25 of one of the clutches, the corresponding disc member 21 being loosely mounted on the spindle and fast with a gear wheel 49 in mesh with a gear wheel 50 secured to the spindle 17. The other clutch device is mounted on the spindle 17, and the drive is transmitted from the clock train gear wheel 15 to the said clutch device, through a gear wheel 51 freely mounted on the spindle 48 and in mesh with a gear wheel 52 freely mounted on the spindle 17 and secured to the ring member 19 of the clutch, the disc member 21 of which is secured to the spindle 17. It will be understood that the disc and ring members of this modification co-operate to form wedge-shaped gaps in which the hollow cylinders are located.

In place of mounting the spindle 48, which carries the gear wheel 51, on a pivotally mounted lever, as in the arrangement of Figures 1 and 2, the spindle is reduced at each

of its ends and the reduced portions extend into slots 53 formed in the side plates 54, 55 of the mechanism, the springs 31 for maintaining the gear wheel 51 in mesh with the gear wheel 15 being secured at one end directly to the spindle.

In this modification also, the single pawl 35 for maintaining the worm wheel 27 in contact with its worm 32 is replaced by a strip 56 of spring steel which is secured at one end to a post 58, and engages at its other end the teeth formed on the gear wheel 47, which is in the gear train driven from the worm 32.

A similar strip of spring steel 57 is secured to the post 59, and engages at its other end the teeth formed on the gear wheel 52 keeping this wheel in engagement with the wheel 51. Either strip of spring steel may be replaced by a spring urged pawl, and either or both strips or pawls may be multiplied on their respective wheels. The shorter the trains of the drives the better the taximeter functions, and the contact holding devices are proportional to the lengths of the trains.

The spindle 48 is driven from the road wheels of the taxicab through a one-way drive device comprising members 60, 61 which are provided with teeth so shaped as to transmit the drive in one direction, and to slip over one another when the taxicab is reversed, a spring 62 being provided for urging the two members towards one another, and a spring-loaded pawl 63 being provided for holding the member 60 against rotation when the other member 61 is reversed.

What I claim is:—

1. In a road wheel and clock drive device for taximeters, the combination of gearing adapted to be driven by the road wheel drive, clock driven gearing, an indicator device operating member, drive mechanism for transmitting drive to the operating member from the gearing driven by the road wheels or from clock driven gearing, whichever be moving at the greater rate, and individual spring means for so urging each gearing as continuously to maintain the drive mechanism associated with each gearing free from backlash with respect to said operating member.

2. In a road wheel and clock drive device for taximeters, the combination of gearing adapted to be driven by the road wheel drive, clock driven gearing, an indicator device operating member, drive mechanism for transmitting drive to the operating member from the gearing driven by the road wheels or from clock driven gearing, whichever be moving at the greater rate, spring means for maintaining the teeth of the gearing driven by the road wheels in contact with each other, and spring means for maintaining the gear wheels driven by the clock in contact with each other so as to prevent lag in operation of said drive mechanism otherwise.

wheel, the said drive devices transmitting drive to the operating member from the worm wheel or from the wheel driven by the clock train drive, whichever be moving at the greater rate.

9. In a road wheel and clock drive device for taximeters, the combination of gearing adapted to be driven by the road wheel drive of the taximeter, spring means urging said gearing so as to maintain the teeth of the gearing in contact with each other, a ring member driven by said gearing, a spindle, a disc fast therewith, the disc and ring member co-operating to provide wedge-shaped gaps, drive transmitting members located in said gaps, a second ring shaped member co-operating with the disc to form an additional series of wedge-shaped gaps, additional drive transmitting members located in said additional gaps, a gear wheel fast with said second ring-shaped member, a clock train drive, spring means for urging the spindle in a direction such that the said gear wheel is maintained in constant engagement with the clock train drive, and a hub wheel driven by said spindle.

10. In a road wheel and clock drive device for taximeters, the combination of a worm adapted to be driven by the road wheel drive, spring means urging said worm in a direction such as to take up wear resulting from the end thrust on the worm, a worm wheel in mesh with the worm, a spring pawl urging said worm wheel in a direction opposite to that in which it is driven by the worm, a ring member driven by said wheel, a spindle, a disc fast therewith, the disc and ring member co-operating to provide wedge-shaped gaps, drive transmitting members located in said gaps, a second ring shaped member co-operating with the disc to form an additional series of wedge-shaped gaps, additional drive transmitting members located in said additional gaps, a gear wheel fast with said second ring-shaped member, a clock train drive, spring means for urging the spindle in a direction such that the said gear wheel is maintained in constant engagement with the clock train drive, and a hub wheel driven by said spindle.

11. In a road wheel and clock drive device for taximeters, the combination of a worm adapted to be driven by the road wheel drive of the taximeter, a spring urging said worm in an axial direction such as to take up wear thereof, a worm wheel in mesh with said worm, spring means urging said wheel in a direction opposite to that in which it is driven by the worm, a ring member driven by said worm wheel, a spindle, a disc fast with said spindle, the disc and ring member co-operating to provide wedge-shaped gaps, cylinders located in said gaps, a second ring-shaped member co-operating with the disc to form an additional series of wedge-shaped gaps, additional cylinders located in said additional

gaps, a rear wheel fast with said second ring-shaped member, a clock train drive, spring means urging the spindle in a direction such that the gear wheel is maintained in constant engagement with the clock train drive, a hub wheel freely mounted on said spindle, and means for transmitting the drive from the spindle to the hub wheel comprising a pin and slot connection device, a plate for determining the effective length of the slot, and means for adjusting the plate, and a spring urging said hub wheel in the direction in which it is driven by the transmitting means.

12. In a road wheel and clock drive device for taximeters, the combination of a worm adapted to be driven by the road wheel drive of the taximeter, a spring urging said worm in an axial direction such as to take up wear thereof, a worm wheel in mesh with said worm, spring means urging said wheel in a direction opposite to that in which it is driven by the worm, a ring member driven by said wheel, a spindle, a disc fast therewith, the disc and ring member co-operating to provide wedge-shaped gaps, cylinders located in said gaps, a second ring-shaped member co-operating with the disc to form an additional series of wedge-shaped gaps, additional cylinders located in said additional gaps, a gear wheel fast with said second ring-shaped member, a clock train drive, spring means for urging the spindle in a direction such that the gear wheel is maintained in constant engagement with the clock train drive, a hub wheel freely mounted on said spindle, means for transmitting the drive from the spindle to the hub wheel comprising a pin and slot connection device, a plate for determining the effective length of the slot, and means for adjusting the plate, and a spring urging the hub wheel in the direction in which it is driven by the transmitting means.

13. In a taximeter, a road wheel driven gearing, motor driven gearing, a spindle, registering means driven by the spindle, a gear journaled on said spindle and in mesh with one of said gearings, means whereby the spindle may bodily move toward the last mentioned gearing to correspondingly move said gear, a plate driven by the gear capable of movement independently of the spindle, a plate driven by the other gearing capable of movement independently of the spindle, and clutch means between said plates and spindle to transmit drive to the spindle according to whichever plate is moving at the greater rate.

14. In a taximeter, a road wheel driven gearing, motor driven gearing, a spindle, register mechanism driven by the spindle, a gear journaled on said spindle and in mesh with one of said gearings, means whereby the spindle may bodily move toward the last mentioned gearing to correspondingly move said gear, a plate driven by the gear capable of movement independently of the spindle,

means urging movement of the latter gearing to take up lag and compensate for movement of the spindle and gear, a plate driven by the other gearing capable of movement independently of the spindle, and clutch means between said plates and spindle to transmit drive to the spindle according to whichever plate is moving at the greater rate.

15. In a taximeter, a road wheel driven gearing, motor driven gearing, a register mechanism driven by both of said gearings, a one way clutch device in each gearing to transmit drive to the register mechanism according to whichever gearing is moving at the greater rate, and means urging relative movement of parts in each gearing to prevent lag of said register mechanism with respect to both gearings otherwise occurring due to backlash in said gearings.

16. In a road wheel and clock drive device for taximeters, the combination of gearing adapted to be driven by the road wheel drive, clock driven gearing, an indicator device operating member, drive mechanism for transmitting drive to the operating member from the gearing driven by the road wheels or from clock driven gearing, whichever be moving at the greater rate, spring means for maintaining the teeth of the gearing driven by the road wheels in contact with each other, and spring means for maintaining the gear wheels driven by the clock in contact with each other so as to prevent lag in operation of said drive mechanism otherwise occurring due to backlash in both of the gear trains, one of said spring means being mounted to exert a thrust upon the teeth of a gear wheel in a direction substantially tangential to the periphery of said wheel.

17. In a taximeter, a road wheel driven gearing, motor driven gearing, a register mechanism driven by both of said gearing, a one way clutch device in each gearing to transmit drive to the register mechanism according to whichever gearing is moving at the greater rate, and means urging relative movement of parts in each gearing to prevent lag of said register mechanism with respect to both gearings otherwise occurring due to backlash in said gearings, said means including a pawl extending substantially radially of a gear wheel in one of said gearings, the free end of the pawl being disposed for engagement with leading tooth surfaces of said gear wheel, and a spring for urging the nose of said pawl in a direction substantially tangential to the periphery of said gear wheel and opposite to its direction of movement.

18. In a taximeter, a road wheel driven gearing including a worm, a thrust bearing therefor, and a worm wheel, a motor driven gearing, a register mechanism driven by both of said bearings, a one way clutch device in each gearing to transmit drive to

the register mechanism according to whichever gearing is moving at the greater rate, and means urging relative movement of parts in each gearing to prevent lag of said register mechanism with respect to both gearings otherwise occurring due to backlash in said gearings, the means urging relative movement of the parts in the road wheel driven gearing including a pawl extending substantially radially of said worm wheel and having its free end disposed for engagement with leading tooth surfaces of said worm wheel, a spring for urging the nose of said pawl in a direction substantially tangential to the periphery of said worm wheel and opposite to its direction of movement, and a spring for urging said worm into contact with said thrust bearing.

19. In a road wheel and clock drive device for taximeters, the combination of gearing adapted to be driven by the road wheel drive, clock driven gearing, an indicator device operating member, drive mechanism for transmitting drive to the operating member from the gearing driven by the road wheels or from clock driven gearing, whichever be moving at the greater rate, spring means mounted to exert a thrust upon the teeth of a gear wheel in the road wheel drive gearing in a direction substantially tangential to the periphery of said wheel for maintaining the teeth of the gearing driven by the road wheels in contact with each other, and spring means mounted to exert a thrust upon the teeth of a gear wheel of the clock driven gearing in a direction substantially tangential to the periphery of said wheel for maintaining the gear wheels driven by the clock in contact with each other so as to prevent lag in operation of said drive mechanism otherwise occurring due to backlash in both of the gear trains.

In testimony that I claim the foregoing as my invention, I have signed my name this 28th day of May, 1930.

FRANK HAROLD CLAUSE.
